UNITED STATES PATENT OFFICE.

WALTER OSTHOFF, OF BARMEN, GERMANY.

SINGEING DEVICE FOR TEXTILE FABRICS.

Application filed December 2, 1921. Serial No. 519,416.

To all whom it may concern:

Be it known that I, WALTER OSTHOFF, a German citizen, residing at Barmen, Germany, have invented certain new and useful Improvements in Singeing Devices for Textile Fabrics, of which the following is a specification.

My invention relates to singeing devices for textile fabrics and more particularly to devices heated by gas and it is an object of my invention to provide for a more economical fuel consumption in such devices.

According to my invention, this object is substantially achieved by providing guide walls on both sides of and at a certain distance from a burner extending across the entire width of the device. The guide walls extend in a vertical direction beyond the base of the flame and deflect in an upward direction the hot gases which tend to flow away from the flame in a lateral direction. The distance between the guide walls and the centre of the burner and their height are such that the guide walls surround the lower edges of a plate-shaped or the lower surface of a cylindrical singeing body. The guide walls may be of sheet metal, fire bricks or the like.

By these means, the hot gases are caused to flow around the singeing body and along the fabric to be singed and to efficiently act upon it. The time required for heating the singeing body before starting the operation is considerably reduced and a material saving of time and fuel is effected. I prefer providing a further guide wall at the side where the fabric enters the device, said wall extending beneath the fabric and substantially in parallel to it and guiding the hot gases toward the incoming fabric, which is thereby subjected to a preliminary drying and heating action. A similar wall may also be provided at the point where the fabric leaves the device.

Preferably, several rows of openings are provided between the burner and the vertical guide walls which are amply supplied with compressed air serving to assist the secondary combustion. By these means not only the fuel is burned more completely but the gases developed by singeing the textile fibres are consumed as well.

In the drawings affixed to this specification and forming part thereof I have il-

lustrated my invention as applied to a burner adapted to be used either without or in combination with flat or cylindrical singeing bodies, the illustrations being merely given by way of example. In the drawings

Fig. 1 is a cross section of the burner with a singeing plate placed thereon, the plate being in course of being heated up.

Fig. 2 is a like view showing means for preliminary drying of the fabric.

Fig. 3 is a cross section of a modified device provided with a singeing cylinder, and

Fig. 4 is a similar view of the burner with the singeing body removed.

Referring to Fig. 1, 1 is the burner proper which is surrounded by a casing 2. The burner 1 comprises two longitudinal channels 9 and 11 which are connected at one end by a passage 10, and an upper longitudinal channel 13 connected with the channel 11 by a passage 12 at the other end. A mixture of gas and air is supplied to the burner through these channels and passages. The mixture enters the channel 9 at one end and leaves it at the other end in order to pass into channel 11, which it flows through in opposite direction. At the other end of this channel it passes through the passage 12 into the channel 13. This channel is provided at the top with a narrow slot 14 from which the flame 5 issues. The burner 1 is strongly heated during operation so that the combustible mixture is preheated by being repeatedly conducted through the burner in opposite directions.

The casing 2 which surrounds the burner 1 after the manner of a jacket is provided with vertical guide walls 3 on either side of the slot 14 which deflect the hot gases spreading on both sides of the flame in an upward direction and toward the fabric 21 to be singed. This deflection of the hot gases may be effected directly by the walls 3, as shown in Fig. 4 or by aid of linings 3^a of fire brick or other suitable material, as illustrated in Figs. 1 to 3. Obviously exchangeable sheet metal walls can be substituted for the bricks.

In the plate singeing device illustrated in Figs. 1 and 2, 4 is an exchangeable singeing plate across which the fabric 21 to be singed is carried. The guide walls which are here formed by bricks 3^a, are so arranged as to surround the edges of the singeing plate 4

- and to deflect the hot gases flowing away on either side of the flame 5 in an upward direction, as indicated by the arrows 6. Here, the remarkable phenomenon has been observed that the hot gases, after having been deflected in an upward direction by the walls 3^a do not proceed further in this direction but adhere to the outer curved surface of the plate 4, as indicated by the arrows 6.
- 10 When there is no fabric on the device, for instance, during the heating up the hot gases follow exactly the contour of the plate until they meet at the centre 8. The currents of air which are produced by the rising of the hot gases follow the gases about the plate 4, as indicated by arrows 7 so that also those gases which flow along the upper surface of the plate 4 are burned completely. This fact together with the circumstance that the plate 20 is completely enveloped by the hot gases, results in a very considerable reduction of the time required for heating-up, thus saving time and fuel.
- Fig. 2 illustrates the operation of the plate singeing device. 21 is the fabric to be singed which is drawn across the heated plate 4 from the right to the left as indicated by the arrow and guided by the rollers 19^a, 19^b and 19^c. The hot gases tend to adhere to the singeing plate 4 as before, but are prevented by the fabric from moving in an upward direction, so that they are partly doubled up and partly flow in the direction of the arrows 6^a and 6^b. On the right, where the fabric enters the device, a guide plate 20 is provided which is connected to the vertical guide plate 3 and extends substantially in horizontal direction. This plate guides the gases which flow as indicated by the arrow 6^a, toward and in opposite direction to the incoming fabric so that the fabric is preheated and subjected to a preliminary drying. In this manner the hot gases leaving the device are utilized very effectively.
- 45 If desired another guide plate 20^a may be provided on the other side of the device in order to maintain the gases leaving on this side in contact with the fabric for a longer time.
- 50 The chamber 16 formed by the casing 2 about the burner 1 serves for supplying and preheating the secondary combustion air which is introduced through an opening 15 in the bottom of the casing 2. In the upper wall 17 of the casing 2 several rows of ports 18 are provided through which the secondary combustion air, after having been preheated by the hot walls of the burner 1 and the ports 18, enters the chambers which are formed at both sides of the flame 5. By the ports 18 which are arranged in several successive rows, so much preheated air is mixed with the hot gases that not only the mixture issuing from the slot 14 is completely burned but there still remains an excess of

air. In consequence thereof, the gases formed by the singeing of the textile fibres are supplied with an amount of air which suffices for complete combustion in the immediate vicinity of the fabric so that the heat produced by the textile fabric on being singed is also utilized in my device.

The quantity of combustible mixture and secondary air can be regulated by valves or cocks, (not shown). The regulation is preferably effected in such a manner as to produce a long and strong flame during heating-up which, as shown in Fig. 1 completely surrounds the plate 4 on all sides so that the plate is heated rapidly. When the plate 4 has reached the predetermined temperature, the supply of combustible mixture may be reduced in quantity and the supply of secondary air increased simultaneously. When the fabric has been introduced, the hot gases will flow as indicated by the arrows in Fig. 2.

When it is desired to use the device in combination with a cylindrical instead of a plate-shaped singeing body, the singeing plate is exchanged for a singeing cylinder 22, as shown in Fig. 3. The cylinder 22 is supported in bearings (not shown) arranged at the ends of the singeing device. Additional guide walls 3^b are provided which adapt the device to the different form of the singeing body and cause the hot gases to follow the same course as indicated in Figs. 1 and 2.

In order to effectively preheat the secondary air, the casing 2 may be filled with some granular substance, such as large pebbles 23 which may also be placed on the plate 17, as shown in Fig. 3. In this manner the area of contact between the air to be preheated and the parts giving off heat is greatly increased and the path of the air is lengthened so that it has a better opportunity for absorbing air from its surroundings.

The example of Fig. 4 shows the device with the singeing body and the bricks 3^a, 3^b removed. It now forms a so called flame singeing device in which the flame acts directly on the fabric 21.

I wish it to be understood that I do not desire to be limited to the exact details of construction shown and described, for obvious modifications will occur to a person skilled in the art.

I claim:

1. In a singeing device for textile fabrics in combination, a casing, a burner surrounded by said casing, means for supplying a combustible mixture to said burner, unperforated spacing means above said burner for conducting a fabric past said burner, and means for deflecting in an upward direction the hot gases spreading laterally from said burner.

2. In a singeing device for textile fabrics

- in combination, a casing, a burner surrounded by said casing, means for supplying a combustible mixture to said burner, an unperforated singeing body arranged in such relation to the burner as to be impinged on by the flame of the burner, and means for deflecting in an upward direction the hot gases spreading laterally from said burner.
3. In a singeing device for textile fabrics in combination, a casing, a burner surrounded by said casing, means for supplying a combustible mixture to said burner, a singeing body arranged in such relation to the burner as to be impinged on by the flame of the burner and means for deflecting the hot gases issuing from said burner in an upward direction, said means being so arranged as to partly surround said singeing body.
- 20 4. In a singeing device for textile fabrics in combination, a casing, a burner surrounded by said casing, means for supplying a combustible mixture to said burner, an exchangeable singeing body arranged in such relation to the burner as to be impinged on by the flame of the burner, and means for deflecting the hot gases issuing from said burner in an upward direction.
- 25 5. In a singeing device for textile fabrics in combination, a casing, a burner surrounded by said casing, means for supplying a combustible mixture to said burner, an exchangeable singeing body arranged in such relation to the burner as to be impinged on by the flame of the burner, and means for deflecting the hot gases issuing from said burner in an upward direction.

combustible mixture to said burner, an exchangeable singeing body arranged in such relation to the burner as to be impinged on by the flame of the burner, and exchangeable plates secured to said casing for deflecting the hot gases issuing from said burner in an upward direction.

6. In a singeing device for textile fabrics in combination, a casing, a burner surrounded by said casing, means for supplying a combustible mixture to said burner, means for conducting a fabric past said burner, means for deflecting the hot gases issuing from said burner in an upward direction and means for deflecting said gases in a direction substantially parallel to said fabric.

7. In a singeing device for textile fabrics in combination, a casing, a burner in the center of the top wall of said casing, means for supplying said burner with a mixture of gas and air, said top wall being provided with openings around said burner, means for supplying said casing and said openings with secondary air, means for deflecting in an upward direction the hot gases spreading laterally from said burner and spacing means above said burner for conducting a fabric past said burner.

In testimony whereof I affix my signature.

WALTER OSTHOFF.
